US00D995913S

(12) **United States Design Patent** (10) Patent No.: **US D995,913 S**
(45) Date of Patent: **** Aug. 15, 2023**

(54) **ELECTRIC DRY SHAVER ATTACHMENT**(71) Applicant: **Braun GmbH**, Kronberg (DE)(72) Inventors: **Philipp Goeder**, Frankfurt (DE);
Gregor Ptak, Frankfurt (DE);
Bernhard Sikora, Kelkheim (DE);
Wolfgang Stegmann, Frankfurt (DE)(73) Assignee: **Braun GMBH**, Kronberg (DE)(***) Term: **15 Years**(21) Appl. No.: **29/781,656**(22) Filed: **Apr. 30, 2021**

(57) CLAIM

The ornamental design for an electric dry shaver attachment, as shown and described.

DESCRIPTION

FIG. 1 is a perspective view of an electric dry shaver attachment;

FIG. 2 is a front view thereof;

FIG. 3 is a left side view thereof;

FIG. 4 is a rear view thereof;

FIG. 5 is a right side view thereof; and,

FIG. 6 is a top plan view thereof.
